United States Patent

Des. 236,141
Patented July 29, 1975

236,141

ACTIVITY TOY

Paul D. Snyder, Allentown, Pa., assignor to The
Quaker Oats Company, Chicago, Ill.

Filed Dec. 5, 1973, Ser. No. 421,772

Term of patent 14 years

Int. Cl. D21—01

U.S. Cl. D34—15 A

FIG. 2

FIG. 1

FIG. 3

FIG. 4

FIG. 5

FIG. 1 is a front elevational view of an activity toy showing my new design, the side opposite being substantially plain and unornamented;

FIG. 2 is a right side elevational view thereof;

FIG. 3 is a top plan view thereof;

FIG. 4 is a bottom plan view thereof; and

FIG. 5 is a left side elevational view thereof.

I claim:

The ornamental design for an activity toy, substantially as shown.
